[57] **CLAIM**

The ornamental design for a lock to be strapped to an automobile handbrake arm and wedged between the arm and floorboard, as shown and described.

DESCRIPTION

FIG. 1 is a front elevational view of a lock to be strapped to an automobile handbrake arm and wedged between the arm and floorboard showing my new design;

FIG. 2 is a rear elevational view thereof;

FIG. 3 is a left side elevational view thereof;

FIG. 4 is a right side elevational view thereof;

FIG. 5 is an enlarged top plan view thereof; and,

FIG. 6 is an enlarged bottom plan view thereof.

FIG. 1

FIG. 2

*FIG. 3**FIG. 4*FIG. 5

FIG. 6
